ATTORNEY

WITNESS:

UNITED STATES PATENT OFFICE.

JOHN KINZEL, OF DETROIT, MICHIGAN.

DIE MECHANISM FOR MAKING REAMERS.

Application filed November 2, 1923. Serial No. 672,404.

To all whom it may concern:

Be it known that I, JOHN KINZEL, a citizen of the United States, residing at Detroit, in the county of Wayne and State of Michigan, have invented new and useful Improvements in Die Mechanism for Making Reamers, of which the following is a specification.

The object of this invention is to provide 10 a machine in which the fluting of stock in the manufacture of reamers may be accomplished by employing a series of forming dies mounted radially with reference to a central point, and adapted to be forced inwardly by rams against the stock while hot, the rams being controlled in the novel manner described below.

A further object is to operate the dies by rams slidable over a stationary body, by 20 the action of knuckle members to which lateral or swinging movement is imparted by an oscillating annular member in which the knuckles are socketed, or with which they are otherwise connected.

25 A still further object is to provide particular means for retaining the dies and stock in position.

With the foregoing and other objects in view, the invention consists in the novel 30 construction and arrangement of elements described and claimed, it being understood that modifications may be made in the scope of the claims without departing from the spirit of the invention.

35 In the drawings, Figure 1 is a top plan view of the machine; Figure 2 is a front elevation, with one side of the housing removed; Figure 3 is a vertical section; Figure 4 is a section on line 4—4 of Figure 3; Figure 5 is a section on line 5—5 of Figure 2; Figure 6 is a perspective view of one of the rams imparting thrust to the dies of Figure 2 under the action of knuckles 28 controlled by the oscillation of ring 22.

40 The base of the machine is designated 10 and has mounted thereon an upwardly extending body 12, which together with a cover 13 forms a housing for the forming dies and the elements operating them.

45 Mounted on the base 10 and a bracket 14 is an electric motor 15, carrying on its armature, shaft 16, a pinion 17 meshing with gear wheels 18 on the shaft 19, and driving a pinion 20 meshing with a rack element 21 50 on an annular element 22 constituting a

toothed ring or rim, mounted in the housing above referred to.

The annular element 22 is oscillated or rotated through a partial revolution and then reversed by reversing the motor automatically, or otherwise. Westinghouse "master switch" No. 214,875 A is employed for this purpose.

The stock to be fluted in the manufacture of the reamer is placed in the machine while 60 hot, and the radial forming dies 25 are forced inwardly by rams 26 slidable between the side walls of the housing, and oscillated by knuckle members 28. Figure 6 is a section on line 5—5 of Figure 2, and 70 these views show that hammers 26 (of Figure 6) have interlocking slidable connection with the edge portions of the independent radial members of stationary spider S mounted in the housing. 75

These elements last named may be socketed in the rams and in the ring 22, each knuckle having having heads 30, 31 on opposite ends thereof. The number of dies corresponds with the number of flutes to be formed in 80 the reamer, and may be greater or less than the number shown in the drawings. Retaining and guiding devices for the reamers are designate 33.

Bolted to the housing, and centrally thereof, is a bracket or frame 35, and a screw 36 is provided with a head 37, and is controlled by a wheel 38. The frame aids in retaining the forming dies in place, and the head prevents displacement of the stock 90 when engaged by the dies.

The threads of the screw are shown as square in cross section and as being formed on two sides of the screw, leaving plane surfaces 36'. These threads are proportioned 95 to engage the segmental threads 40 on the parallel elements 41 of the frame, the screw being thus adapted for release upon a quarter turn. The end cap 44 is secured by bolts 45, and serves to guide the screw in its movement.

The stock is placed in position between the radial dies when the latter are at their outer limit of movement, and the knuckles 28 are at an angle with reference to the path of travel of the dies. The motor is then started, thereby imparting drive to ring 22, by pinion 20, and throwing knuckles 28, constituting levers, to the position of Figure 1, in which they are in alinement with the 110

radial dies. This causes the dies to perform the fluting operation, the stock being withdrawn when the motor has reversed and the dies are at their outer limit of movement.

5. What is claimed is:—

1. In a die mechanism, a series of radially movable dies, rams engaging the dies, an oscillating ring member surrounding the rams, devices for imparting movement from 10 the ring to said rams, said devices having heads on opposite ends, the heads being socketed in the rams and in the ring, and a spider including grooved radial elements with reference to each of which one ram 15 has interlocking slidable connection, independently of adjacent elements of the spider.
2. In a die mechanism, a series of radially movable dies, rams engaging the dies, an oscillating ring member surrounding said 20 rams, devices for imparting movement from the ring to said rams, and means for guid-

ing the rams, said means including a spider comprising grooved radial arms with reference to each of which one of the rams has interlocking slidable connection, independently of adjacent arms of the spider.

3. In a device of the class described, a housing having an opening in the side thereof, radially movable dies mounted in the housing, the stock to be operated on by the dies being positioned to pass through the opening, spaced means projecting outwardly from the housing on opposite sides of the opening and having threads thereon, and a screw including segmental threads engaging the threads first named, and including flat sides between the segmental threads, said screw also including a head for engaging the work.

In testimony whereof I affix my signature.

JOHN KINZEL.
